UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF ATTACHING HEELS TO SHOES.

Application filed December 14, 1922. Serial No. 606,880.

This invention relates to methods of making shoes and will be explained, for the purpose of illustration, by describing its application to the attaching of wood heels to women's 5 shoes, although in various respects the invention is not limited to the attachment of wood heels.

In U. S. Letters Patent No. 1,615,258, granted Jan. 25, 1927, on application of M. 10 V. Bresnahan, there is described a method of temporarily attaching wood heels to shoes by passing a screw fastener through a hole in the rear end of a last in a shoe and through the heel-seat portion of the shoe bottom into 15 a heel to secure the last, the shoe and the heel together so that various operations can be performed upon the heel or the shoe without waiting for heel attaching adhesive to dry. In accordance with this method not only is 20 the heel securely held in place against the heel seat of the shoe during the drying of the adhesive but the shoe and last are clamped together in such a manner that the last distributes the clamping pressure over the entire 25 heel-seat portion of the shoe. Thus, the latter is compressed between the heel and the last to conform the heel seat to the attaching face of the heel under pressure, thereby insuring firm seating of the heel and the provision of a tight joint between the shoe upper 30 and the rim around the seat face of the heel.

In view of the foregoing, one object of the present invention is to provide an improved method of attaching heels to shoes 35 which, while retaining all the advantages of the Bresnahan method above referred to, will facilitate the attachment of heels without the employment of adhesive and which, in practice, will effect further improvements in the 40 attachment of heels whether with or without the use of adhesive.

To this end, the invention, in one respect, provides for the attachment of a heel to a shoe by utilizing a fastening designed to remain in the shoe as a permanent fastening, and for the clamping of the last to the shoe and heel by a member engaging said fastening, and adapted to be withdrawn to permit the removal of the last from the shoe without disturbing the attachment of the heel to the shoe. As herein exemplified, one of two separable members of a compound fastener is passed through a hole in the last without holding engagement with the last and

through the shoe bottom into the central portion of the heel attaching face of the heel to serve as a permanent heel fastening, while the other member is passed through the hole in the last and clamps the last to the shoe and heel by holding engagement with the last and by detachably engaging the permanent heel fastening member. Thus, if it is not desired to employ heel attaching adhesive, the last or the heel end portion of the last may be removed from the shoe without disturbing the attachment of the heel to facilitate the driving of heel attaching nails from the inside of the shoe into the heel, for example. At the same time, if adhesive be employed, any desired operations may be performed before the adhesive is dry, regardless of whether the heel end portion of the last is removed. Moreover, the insertion of a permanent heel fastening into the central portion of the heel supplements the heel attaching nails and strengthens the permanent attachment of the heel.

The manner in which the above and other objects of the invention are secured will be apparent from the following description of the way in which one illustrative form of apparatus shown in the accompanying drawings is used in attaching a heel.

In these drawings:

Figure 1 is a front elevational view showing part of a heel attaching machine of the type illustrated in United States Letters Patent No. 1,664,657, granted April 3, 1928, upon my co-pending application and also special apparatus for use in connection with the compound fastener herein described;

Fig. 2 is a side elevation partly broken away showing the drilling of a hole of predetermined depth in a heel;

Fig. 3 is a similar view showing the insertion of one of the above described permanent heel fastenings through a last into a heel;

Fig. 4 is a side elevation of the drill shown in Fig. 2;

Fig. 5 is a similar side elevation of a modified form of drill;

Figs. 6 and 7 are respectively top and side views of one of the permanent heel fastenings;

Figs. 8 and 9 are respectively a top and a side view of a modified form of fastening; and

Figs. 10 and 11 are respectively top and

bottom plan views of the separable part of the above described compound fastening device.

In carrying out the invention as illustrated 5 in the drawings, a last and shoe and heel are preliminarily clamped together by means fully illustrated and described in my above identified Letters Patent. The heel is firmly supported by a tread plate 10 and a vertically 10 adjustable rear support 12 carried by a post 14 mounted on a table 16.

As shown in Fig. 2, while the last and shoe and heel are held preliminarily clamped as described, a drill is inserted through a hole 15 passing through the rear end of the last and is guided by the hole in the last to drill a hole of predetermined depth through the heel seat of the shoe into the heel. The illustrated drill comprises a shank 18 clamped in a chuck 20 carried at the bottom of a flexible drive shaft 22, the bottom end of the shank being formed into a cutting drill 24. A sleeve 26 is adjustably clamped to shank 18 by means of a set screw 28 and acts as a guide to direct 25 the drill axially of the hole in the last. The bottom of sleeve 26 serves as a shoulder to engage the top of the sole of the shoe to limit the operation of drill 24 in such a manner as to form a hole of predetermined depth. If 30 the sole is of very firm stock so that the head of the screw does not readily crowd into it so as to be flush with its upper surface, the hole made by the drill may be countersunk by forming the bottom of sleeve 26 as a counter- 35 sinking drill 30, as shown in Fig. 5.

After the heel has been prepared by drilling a hole as above described, my improved two-part fastening device is inserted in the 40 hole in the last. This device comprises an upper part 32 having a driver-engaging reduced top part 34 (Figs. 3 and 10) and a central threaded stem 36 (Fig. 11) on its lower end. The stem 36 is arranged to seat in a threaded recess 38 formed in the head 40 of 45 a permanent heel fastening such as a threaded screw 42. If desired, a slot 44 (Fig. 8) may be formed in the head 40 of the screw so that the screw may be removed without undue difficulty if it is necessary to remove the heel in 50 repairing the shoe. The upper or driving part 32 and the screw 42 are threaded together when they are inserted in the hole in the last, and the head 34 is engaged by a power-driven screw-inserting implement 46 constructed as 55 described in my above identified Letters Patent. The parts are held in the relative positions shown in Fig. 3 until the screw 42 is driven home with its head substantially flush with the upper surface of the sole of the shoe.

In order to clamp the last firmly to the 60 permanent heel fastening 42, a last clamping member 48 is threaded on the upper end of the shank part of the driving member 32 in such a manner that it may be turned down against 65 the top of the last. Preferably a leather or

other compressible washer 50 is provided. As shown in Fig. 1, I prefer to provide an improved form of socket wrench including a manipulating handle 52 in which a wrench member 54 is mounted for turning movement. 70

The improved wrench may conveniently be carried by a cord 56 attached to a weight 58, the cord passing over a pulley 60 carried by a bracket 62 adjustably clamped to a post 64 mounted on the table 16. By this arrangement, when the operator lets go of the wrench

it will automatically return to the inoperative position shown in dotted lines in Fig. 1. The wrench member 54 is formed at its lower end to engage the sides of the last clamping member 48 and is provided with a cylindrical recess 66 to avoid the possibility of engaging 80 the head 34 of the driving member 32. The wrench member is also formed with an upwardly projecting head 68 of substantially

the same form as the head 34 to turn the last clamping member 48 firmly down against the top of the last. The last and the shoe and the heel having been firmly clamped together as 85 shown in Fig. 1, various finishing or other operations may be performed upon the shoe

as mentioned in the above described Bres- 90 nahan patent. The screw driving member 32 is then withdrawn by turning it in the reverse direction, whereupon the stem 36 and the member 32 separate from the recess 38 in the screw 42, leaving the fastening 42 per- 95 manently securing the shoe and heel together. Thereafter, the last may be removed from the shoe, the heel further secured by inside nail- 100 ing in the usual way if desired and further operations performed upon the shoe in any usual manner.

The improved fastening device described 105 above is not claimed herein but is described and claimed in an application for United States Letters Patent Serial No. 288,620, filed June 27, 1928, as a division of the present application.

While one method of procedure has been 110 particularly described, it is not my intention to limit the scope of the invention thereby or otherwise than by the appended claims when construed in the light of the prior art.

Having thus described my invention, what 115 I claim as new and desire to secure by Letters Patent of the United States is:—

1. That method of making shoes which 120 comprises the step of permanently securing a heel to a shoe and simultaneously temporarily securing a last to the shoe and heel by means of a compound fastening having a first portion to remain in the shoe as a permanent fastening and a second and removable portion comprising a shank to pass through a hole in the last and a part to engage the top of the last to press the last and heel and shoe together.

2. That method of making shoes which 125 comprises the step of permanently securing a 130

heel to a shoe and simultaneously temporarily securing a last to the shoe and heel by means of a compound fastening having a first portion to remain in the shoe as a permanent fastening and a second portion to clamp the last temporarily to the shoe and heel through the medium of the first portion.

5. That method of making shoes which comprises the step of permanently attaching a heel to a shoe on a last by a fastening passed through a hole in the rear end of the last, temporarily clamping the last to the shoe by means of a device engaging the last and said fastening, and thereafter disengaging said device from said fastening to permit withdrawal of the last from the shoe.

10. That method of making shoes which comprises the step of permanently securing a heel in place upon a shoe by a fastening, and temporarily securing a last to the shoe and heel by clamping it to the fastening in such a manner as to leave the exterior of the shoe unobstructed.

15. That method of making shoes which comprises the step of securing a heel and shoe together by a member designed to remain in the shoe as a permanent fastening, and temporarily clamping a last in the shoe to the permanent fastening.

20. 6. That improvement in methods of making shoes which comprises the steps of attaching a heel and a shoe together by a fastening passed through a hole in the rear end of a last in the shoe without clamping the last to the shoe, and thereafter 25 the shoe, and thereafter, while the heel and

the shoe are maintained attached together, temporarily clamping the last to the shoe and heel by a device engaging the last and said fastening.

7. That improvement in methods of making shoes which comprises attaching a heel to a shoe by a fastening designed to serve as a permanent fastening and passed through a hole in the rear end of a last in the shoe without holding engagement with the last and 45 through the shoe bottom into the central portion of the heel, and thereafter temporarily clamping the last to the shoe and heel by a member passed through the hole in the last in holding engagement with the last and detachably engaging the said permanent heel fastening.

8. That improvement in methods of making shoes which comprises supporting a heel and a shoe on a last in assembled relation, attaching the heel to the shoe by a fastening passed through a hole in the rear end of the last without clamping the last to the shoe, and thereafter temporarily securing the last to said fastening.

60 9. That improvement in methods of making shoes which comprises attaching a heel to a shoe by a fastening passed through a hole in the rear end of a last in the shoe without clamping the last to the shoe, and thereafter 65 utilizing said fastening in temporarily clamping the last to the shoe and the heel.

In testimony whereof I have signed my name to this specification.

FREDERIC E. BERTRAND.
